UNITED STATES PATENT OFFICE.

ARCHIBALD McGUFFIE, OF ROCHESTER, NEW YORK.

RAILROAD-CHAIR.

Specification of Letters Patent No. 31,816, dated March 26, 1861.

To all whom it may concern:

Be it known that I, ARCHIBALD McGUFFIE, of the city of Rochester, in the county of Monroe and State of New York, have made 5 and invented certain new and useful Improvements in Railroad-Chairs, of which the following is a full and accurate description, reference being had to the accompanying drawings, making part of this specification, 10 and to the letters of reference marked thereon, same letters referring to like parts in all the figures.

Of these drawings Figure 1 is a perspective view of the underside of my improved 15 chair as connecting two sections of rail. Fig. 2 is a plan of the same showing the method of attaching it to the sleepers. Figs. 3, 4, 5, 6 and 7 are details.

The nature of this invention consists in di- 20 viding the chair longitudinally into two wedge-shaped sections—one section being provided with a tongue and the other with a corresponding groove so that they may clamp the sections of the rail and hold them 25 firmly by merely driving them together.

The construction of the aforesaid chair is as follows: The section B (Fig. 1) being constructed as shown in plan and section in 30 Figs. 5 and 6—that is to say having the edge c inclined to the line of the groove b which receives the rail and also having the groove or hook h attached to the edge x and parallel with it; and the section A of said rail (Fig. 1) being constructed as shown in 35 Figs. 3 and 4 that is to say having the edge a corresponding to the edge x of section B but contrary thereto and having the wedge d formed so as to fit into the groove or hook h , as seen in Figs. 1 and 7; it is evident that on 40 placing the edge a in contact with the edge c and the wedge d in the groove h (as shown in Fig. 7); the distance apart of the outer edges of the combined sections will depend upon the relative longitudinal positions of 45 the two sections A and B. Thus if A (Fig. 1) be driven toward the left while B is kept stationary the space destined to receive the

rail will be lessened and the rail will be tightly clasped by the chair. Hence in order to use this chair it is merely necessary 50 to place the two ends of the rail together, and then adjust the two sections of the rail, one on each side, bringing the wedge d into proper position in regard to the groove h and driving the two sections of the chair toward each other. They may then be spiked 55 to the sleepers either by spikes driven through notches formed in the sides of the chair, or if it be made without these notches a spike driven at the wide end of each section of the chair will prevent their coming 60 apart.

It will be seen that this chair not only holds the sections of the rail firmly together but it may be tightened upon the rail without any tendency to throw the sections of the rail out of line as chairs are very apt to do when a common wedge is used to fasten them to the rail by driving it between the latter and the chair. For as the sections of 70 the chair approach equally from both sides everything is kept even and in line. Neither is there any complication about the different parts or about their use. The whole arrangement is simple and effective and may 75 be used by any laborer while from the closeness with which the whole chair is drawn to the rail it adds materially to the strength of the junction—this also being increased by the extra material forming the wedge and 80 groove.

Having thus described my invention what I claim therein as new and desire to secure by Letters Patent is—

Dividing the chair into two wedge shaped 85 sections A and B provided respectively with the groove or hook h and wedge d —the whole operating in the manner and for the purpose substantially as described.

ARCHIBALD McGUFFIE.
